FRANK H. NICHOLSON, OF LEWISTOWN, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 17, 1923. Serial No. 663,084.

To all whom it may concern:

Be it known that I, FRANK H. NICHOLSON, a citizen of the United States, residing at Lewistown, in the county of Mifflin and State of Pennsylvania, have invented certain new and useful Improvements in Railway-Traffic-Controlling Apparatus, of which the following is a specification.

My invention relates to railway traffic controlling apparatus, and particularly to apparatus of the type comprising train carried governing apparatus controlled in part by energy received from the trackway. More particularly my invention relates to the train carried portion of such apparatus.

I will describe one form of apparatus embodying my invention, and will then point out the novel features thereof in claims.

The accompanying drawing is a diagrammatic view showing one form and arrangement of train carried railway traffic controlling apparatus embodying my invention.

Referring to the drawing, the reference character D represents a three-way valve mounted on a railway vehicle and controlled by traffic conditions in advance of the vehicle. The means for controlling this valve D are not essential to the complete disclosure of my invention and are omitted from the drawing for the sake of simplicity. It is sufficient to say that when traffic conditions in advance are safe, that is, such as to permit the train to travel at high speed with safety, this valve D connects pipe 1 with pipe 2. When traffic conditions in advance are such as to require caution, that is, to impose an intermediate speed limitation, valve D connects pipe 1 with pipe 3. When traffic conditions in advance of the train are dangerous, or such as to impose a low speed limitation, valve D connects pipe 1 with pipe 4, which may be connected, by means hereinafter described to pipe 32. Pipe 1 contains a fluid, as air, under pressure greater than atmosphere and when this pipe is vented to atmosphere the brakes on the train are applied by automatic means not shown in the drawing.

Mechanically driven by an axle F of the train is a centrifugal device A comprising, as shown in the drawing, a pair of weights 5 each connected to an arm 10. These arms 10 are pivotally supported at point 10^a and are so disposed that when the weights 5

are rotated by the axle F the centrifugal force so created tends to move weights 5 outward thus moving collar 12 toward the left against the biasing force exerted by a coil spring 11. A crosshead 13 is operated by the collar 12 of centrifuge A. The centrifugal force exerted by weights 5 is a function of their speed which is in turn proportional to the speed of the vehicle, and it therefore follows that for any speed of the vehicle, there is one, and only one, position of crosshead 13.

The reference character X designates a valve body comprising three valves L, M and H. Each of these valves is contained in a chamber 16 provided with an opening normally closed by the valve. Each valve is held closed by a spring 16 and is provided with a stem 15. When the valves are moved toward the left, the chambers 16 are connected to atmosphere. These valves are so disposed and the stems 15 are so proportioned that when the speed of the train exceeds some low value as 15 miles per hour, crosshead 13 engages stem 15 of valve L and opens its chamber to atmosphere; when the train exceeds some intermediate speed, as 35 miles per hour stem 15 of valve M is engaged by crosshead 13 and valve M is opened; and when the train exceeds some high speed as 65 miles per hour the valve H is opened.

Chamber 16 of valve H is connected with pipe 2, chamber 16 of valve M is connected with pipe 3 and pipe 4 is connected, through certain apparatus to be hereinafter described, to chamber 16 of valve L.

The operation of the apparatus so far described is as follows:

As shown in the drawing, valve D is in the high speed position, so that pipe 1 is connected, by means of valve D and pipe 2, with valve H, and the governing apparatus will allow the train to proceed at any speed below 65 miles per hour. If, however, the speed of the train exceeds 65 miles per hour the centrifuge crosshead 13 will engage stem 15 of valve H, thus opening this valve and applying the brakes. If the train were traveling under an intermediate speed limitation pipe 1 would be connected, by means of valve D and pipe 3, with valve M, and the brakes would be applied as soon as the speed of the train exceeded 35 miles per hour. Similarly

if the valve D were in such position that pipe 1 were connected with valve L, that is, when the train is under a low speed limitation, the brakes would be applied if the speed of the train exceeded 15 miles per hour.

Under some conditions of operation, it becomes desirable for the engineman of a locomotive carrying governing apparatus such as has been described, while operating under a low speed limitation, to temporarily increase the speed of the locomotive above 15 miles per hour without incurring an automatic brake application. Such a condition of operation is met with in practice when an engineman wishes to "make a flying switch", that is, when he wishes to disconnect the front portion of the train from the rear portion while the train is in motion and approaching a switch, and subsequently to increase the speed of the locomotive so that the front portion of the train draws away from the rear portion far enough to enable the attendant to operate the switch after the passage of the front portion of the train and before the transit of the rear portion, thus routing the two sections of the train upon different tracks. It has been found in practice that to safely negotiate a flying switch it is desirable to increase the speed of the front portion of the train above 15 miles per hour till it has passed the switch. With only the apparatus thus far described, if the traffic conditions impose a low speed limitation upon the train the brakes will be applied as soon as the speed of the locomotive exceeds 15 miles per hour.

In my invention I provide means for delaying the application of the brakes for a definite interval of time after the speed of the locomotive, running under the low speed limitation, has exceeded 15 miles per hour. This means comprises a timing valve K comprising a cylinder 18 divided by a reciprocable piston 19 into an upper chamber 23 and a lower chamber 22. The joint between the walls of the cylinder 18 and piston 19 is sealed by means of a piston ring 20 inserted in an annular groove in the wall of the piston. Air under a constant pressure greater than atmospheric is admitted to the chamber 22 under the piston 19 from some suitable source through pipe R and tends to push the piston to its upper position against the biasing force exerted by a spring 21. A valve 25 is biased to its closed position by a spring 26 and is operated by a plunger 24 which is biased to an inoperative position by a spring 27. When the piston rises, it moves plunger 24 upward into engagement with the stem of valve 25, thus permitting passage of air from chamber 30 to chamber 28. Chamber 30 is constantly connected with pipe 4, and chamber 28 is constantly connected with pipe 32. Means are also pro-

vided for allowing spring 21 to move piston 19 to its lower position. This is accomplished by supplying air to the upper part of cylinder 18 at a pressure equal to or greater than that supplied below. I accomplish this as follows:

A valve C similar to valves L, M and H, is operated by centrifugal device A and is so arranged that when the speed of the train is 8 miles per hour or below, the crosshead 75 13 engages the stem 15 of this valve thereby connecting chamber 16 of valve C with pipe 7. Chamber 16 of valve C is constantly connected by means of pipe 1^a with a supply of air from the same source as that which supplies pressure to valves H, M and L from pipe 1. That is, pipe 1^a is connected with pipe 1 so that the brakes will be automatically applied if the pressure in pipe 1^a is sufficiently reduced. It is clear that this pressure is applied to pipe 7 only when valve C is open.

A second centrifugal device B similar to device A, is also driven by axle F, but by a separate driving connection, and operates a plunger 13^a. A valve G, similar to valve L, H and M, is controlled by plunger 13^a in such a manner that when the speed of the train is above 12 miles per hour the plunger 13^a engages the stem 15 of valve G and opens chamber 16 of valve G to atmosphere. Since this chamber is connected with pipe 7, the opening of valve G will vent pipe 7 to atmosphere at all speeds above 12 miles per hour. A reservoir E is connected with pipe 7 through a check valve 9 and a restricted charging port 8. This reservoir is connected by means of pipe 6, with chamber 23 above piston 19. This chamber 23 is also connected through 105 a restricted passage 29, with pipe 32. Valves G and C, together comprise means for detecting the integrity of the driving connection between axle F and centrifugal device A, for if this driving connection 110 should fail, device A will be at rest while the train is in motion causing cross-head 13 to open valve C to admit pressure from pipe 1^a to pipe 7. If the speed should then exceed 12 miles per hour, valve G will open thus venting pipe 1^a directly to atmosphere to apply the brakes. The purpose of check valve 9 is to prevent exhaust of pressure from reservoir E through valve G when the latter is open. The purpose of restricted port 8 is to prevent a material reduction in pressure in pipe 1^a while charging reservoir E.

The lower surface of piston 19 is provided with an annular groove filled with packing 40 which engages a circular rib 41 on the bottom of the cylinder 18 and seals off the chamber 22 communicating with the pressure source R. A circular rib 36 on the top of piston 19 engages in a similar manner 130

the surface 37 when the piston rises, and so there is no loss of air pressure from source R in either position of piston 19. A small throttling passage 35 connects the outer annular portion of chamber 22 with chamber 23 when piston 19 is in the lower position, so that the area exposed to the pressure in pipe R is substantially less when valve 19 is in the lower position than when it is in an intermediate or the upper position. That is, when piston 19 starts to move upward, the piston area upon which the pressure in pipe R is exerted is substantially increased, thus insuring a rapid and positive movement of the piston to its upper position.

I will assume that the train is proceeding under the low speed limitation, that is, with valve D connecting pipe 1 with pipe 4, at a speed below 8 miles per hour. Valve C is then open, valve G is closed and pressure from pipe 1^a is available to charge reservoir E through pipe 7 and restricted port 8. The reservoir E is connected with chamber 23 and as soon as reservoir E is partially charged, the combined force exerted by this pressure and spring 21 forces piston 19 downward against the pressure admitted to chamber 22 by pipe R. While piston 19 is up, pressure is also admitted to E from pipe 1 through valve D, pipe 4, valve 25 to pipe 32, thence through port 29 to chamber 23, thence through pipe 6 to reservoir E. When piston 19 moves downward, pipe 4 is cut off from pipe 32 by the closing of valve 25. I will now assume that the engineman increases the speed of the train, as to negotiate a flying switch. As the speed exceeds 8 miles per hour valve C will close, thus disconnecting pipe 1^a from pipe 7. As the speed exceeds 12 miles per hour valve G opens thus venting pipe 7 to atmosphere, but check valve 9 prevents the escape of air from reservoir E which is now charged to the same pressure as 1^a, and consequently no change is made in the condition of timing valve K. As the train exceeds 15 miles per hour, valve L is opened and the air under pressure in chamber 23 and reservoir E is slowly exhausted to atmosphere through restricted port 29, pipe 32 and valve L. The brakes, however, do not apply, because pipe 4 is cut off from pipe 32 and valve L by valve 25. If now the train continues above 15 miles per hour until the pressure in chamber 23 is so reduced that the force exerted by pressure on the lower side of piston 19 is enough to raise the piston 19 against the combined force of spring 21 and the air pressure in chamber 23, the piston moves to its upper position, opening valve 25 and allowing pipe 1 to vent through valve D, pipe 4, chamber 30, valve 25, chamber 28, pipe 32 and valve L, to atmosphere, thus applying the brakes.

It is therefore plain that an engineman running under low speed limitation, may increase the speed of the train above 15 miles per hour for a limited time and may avoid incurring an automatic brake application as a result of exceeding the low speed limitation, by reducing his speed to less than 15 miles per hour before the completion of the time interval required to blow down reservoir E to actuate the valve device K.

It should be pointed out that piston 19 may be retained in its lower position only when the speed of the train is below 15 miles per hour, and that the timing valve K is operative only for low speed limitation. Under other circumstances the operation of the system is in no wise affected by this valve. For example, if we assume that valve D is in the high speed position, connecting pipe 1 to pipe 2 and the train is above the speed at which valve L is open, piston 19 is held in the upper position, so that upon a change in position of valve D from high speed to low speed positions, pipe 1 will be connected through pipe 4 to valve L to render the low speed limit immediately effective.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising normally inactive means for applying the brakes on a vehicle, a speed responsive device for co-operation with said means to cause an application of the brakes, and speed responsive means for preventing such co-operation for a fixed interval of time.

2. Railway traffic controlling apparatus comprising normally inactive means for applying the brakes on a vehicle, a speed responsive device for co-operation with said means to cause an application of the brakes, means for preventing such co-operation for a fixed interval of time, and speed responsive means for rendering such last mentioned means effective.

3. Railway traffic controlling apparatus, comprising automatic brake application mechanism, a speed responsive device on a vehicle for co-operating with said mechanism to cause a brake application if the vehicle exceeds a given low speed and traffic conditions in advance are dangerous, and means for preventing said co-operation for a fixed interval of time if said vehicle exceeds such speed.

4. Railway traffic controlling apparatus

- comprising automatic brake application mechanism comprising a pipe containing fluid pressure and adapted to apply the brakes when such pressure is reduced, a speed responsive valve, means normally effective to connect said valve with said pipe and means controlled by said valve and effective for an interval of time to prevent connection of said valve with said pipe.
10. 5. Railway traffic controlling apparatus comprising a pipe, automatic brake application mechanism controlled by fluid pressure in said pipe, a speed responsive valve, normally effective means for connecting said valve with said pipe, a reservoir for containing air under pressure, means responsive to said pressure for placing said means in ineffective condition, and speed responsive means for supplying air to said reservoir only when the speed is below a very low value.
15. 6. Railway traffic controlling apparatus comprising automatic brake application mechanism on a vehicle, a speed responsive valve for co-operating with said mechanism to cause a brake application, means for rendering said valve ineffective for a given interval of time, and speed responsive means for rendering the said means ineffective for vehicle speeds above a given value.
20. 7. In combination with a railway air brake system comprising a pipe containing air under pressure greater than atmospheric whereby the brakes are applied on a vehicle when said pressure is reduced, a valve responsive to the speed of the vehicle and opened at a low speed, means for at times connecting said pipe with said valve, a device interposed between said valve and said means, and capable when in its operative position but not when in its inoperative position of interrupting the communication between said means and said valve, a reservoir for containing air under pressure, means for charging said reservoir when the vehicle is at rest or proceeding at a very low speed, and means controlled by the pressure in said reservoir for moving said device to its operative position.
25. 8. In combination on a vehicle, means responsive to traffic conditions in advance of the vehicle for causing a brake application when the vehicle exceeds a given speed, a pipe, means effective when said vehicle is at rest or moving at a very low speed to supply said pipe with fluid pressure, and means responsive to the pressure in said pipe for delaying said brake application.
30. 9. In combination, an automatic brake applying mechanism on a vehicle comprising a pipe containing fluid pressure adapted to cause a brake application when such pressure is reduced, a valve adapted to be opened when the speed of the vehicle exceeds a predetermined value, means respon-
- sive to traffic conditions for at times connecting said pipe with said valve, and means interposed between said valve and said pipe for temporarily preventing a brake application when said valve is opened.
35. 10. In combination, a railway vehicle provided with braking mechanism, a pipe 1 normally charged with fluid pressure and arranged to cause an automatic brake application when such pressure is reduced, a valve L biased to the closed position, speed responsive means on the vehicle for opening said valve when the speed exceeds a given low value, means on the vehicle controlled by traffic conditions in advance and normally effective to connect said pipe with said valve under low speed traffic conditions, a valve 25 effective when closed to prevent connection between pipe 1 and valve L, a piston 19 biased to one position in which it opens valve 25, and means effective when the speed of the vehicle is reduced below said given low value for moving said piston to another position and keeping it there for a fixed interval of time after the vehicle subsequently exceeds said given low value.
40. 11. In combination, a railway vehicle provided with braking mechanism, a pipe 1 normally charged with fluid pressure and arranged to cause an automatic brake application when such pressure is reduced, a valve L biased to the closed position, speed responsive means on the vehicle for opening said valve when the speed exceeds a given low value, means on the vehicle controlled by traffic conditions in advance and normally effective to connect said pipe with said valve under low speed traffic conditions, a valve 25 effective when closed to prevent connection between pipe 1 and valve L, a piston 19 biased to one position in which it opens valve 25, means effective when the speed of the vehicle is reduced below said given low value to apply fluid pressure to said piston for moving the piston against said bias to a position in which it allows valve 25 to close, and means controlled by valve L for gradually reducing the pressure applied to said piston after the vehicle subsequently exceeds said given low value.
45. 12. In combination, a railway vehicle provided with braking mechanism, a pipe 1, normally charged with fluid pressure and arranged to cause an automatic brake application when such pressure is reduced, a valve L biased to the closed position, speed responsive means on the vehicle for opening said valve when the speed exceeds a given low value, means on the vehicle controlled by traffic conditions in advance and normally effective to connect said pipe with said valve under low speed traffic conditions, a valve 25 effective when closed to prevent connection between pipe 1 and valve L, a piston 19 biased to one position

in which it opens valve 25, a reservoir for applying pressure to said piston to move the piston against said bias to a position in which it allows valve 25 to close, speed responsive means for charging said reservoir with fluid pressure when the speed of the vehicle is reduced below said given low value, and means controlled by valve L and effective when the vehicle subsequently exceeds said given low value to gradually reduce the pressure thus applied to piston 19. 10

13. In combination, a railway vehicle provided with braking mechanism, a pipe 1 normally charged with fluid pressure and arranged to cause an automatic brake application when such pressure is reduced, a valve L biased to the closed position, speed responsive means on the vehicle for opening said valve when the speed exceeds a given low value, means on the vehicle controlled by traffic conditions in advance and normally effective to connect said pipe with said valve under low speed traffic conditions, a valve 25 effective when closed to prevent connection between pipe 1 and valve L, a piston 19 biased to one position in which it opens valve 25, a reservoir for applying pressure to said piston to move the piston against said bias to a position in which it allows valve 25 to close, speed responsive means for charging said reservoir with fluid pressure when the speed of the vehicle is reduced below said given low value, means for preventing escape of such pressure from said reservoir when the speed of the vehicle is below said given low value, and means controlled by valve L, and effective when the vehicle subsequently exceeds said given low value to gradually reduce the pressure thus applied to piston 19. 15 20 25 30 35 40

In testimony whereof I affix my signature.
FRANK H. NICHOLSON.
